FOLDING HOOD

Francis Henry Redfern, Folkestone, England

Application November 11, 1936, Serial No. 110,350
In Great Britain August 5, 1936

5 Claims. (Cl. 296—117)

This invention relates to folding hoods for motor and other road vehicles and for means of conveyance whether by land, sea or air, herein-after termed "vehicles", of the type comprising 5 main pillars pivoted towards the rear of the vehicle and carrying at their ends cant rails (preferably formed by rear and front sections) the outer ends of which are connected, for example by a front cross-bar (from which the hood fabric 10 extends to the back of the body) a suitable linkage or otherwise effecting the co-operative movements of the parts when the main pillars are caused to turn about their aligned pivots.

The principal object of the invention is to provide simple and efficient hydraulic means by 15 which the main pillars are turned in order to effect the erection or folding of the hood as the case may be.

A further object is to provide such hydraulic 20 means to operate in both directions, that is, for both the erection and the folding actions.

For this purpose the invention comprises a double-acting hydraulic cylinder and piston and piston rod, ram or plunger assembly, which is 25 pivotally connected on the one hand to the frame, bodywork or chassis of the vehicle at a fixed point and on the other hand to the main pillar. Such an arrangement comes on each side of the vehicle or the like, each cylinder having means 30 of connection to a controlled supply of pressure fluid for the projection and retraction of the piston rod, ram or plunger means from or into the cylinder.

The arrangement of the double-acting assembly 35 is such that the pressure fluid effects both the erection and collapsing of the hood and the operation takes place through piston means having differential areas on the two effective working faces thereof.

40 In addition, suitable valve or other control devices are provided for the erection and/or the collapse of the hood to bring it into the required position at will.

According to another and important feature 45 of the invention, in place, as has been usual, of pivoting the main pillars to the bodywork or coachwork of the vehicle or the like, the two main pillars (one on each side) are connected to either a portion of the chassis itself (as dis- 50 tinct from the bodywork) or to a member connected to the chassis. This enables the hood structure as a framework without the covering or any other part of the bodywork being present 55 to be assembled on the chassis independently of the bodywork, thus giving maximum rigidity.

According to more particular features of the invention, the hydraulic action takes place through a pump and suitable conduits (preferably in connection with a suitable supply reservoir) so that upon the operation of the pump, 5 according to the particular arrangement and the setting of the valves, the hood is erected, or collapsed, either action being cushioned if desired.

According to a still further and more particular feature of the invention, the hydraulic pump 10 may be power-operated, for example by means of an electric motor driven by suitable means such as an accumulator which may be the accumulator of the vehicle, or by the engine of the 15 vehicle or otherwise.

In one particular structure according to this last mentioned feature, a rotary pump may be employed mounted through a suitably cushioned or other coupling directly (or through suitable 20 gearing) on the shaft of an electric motor, the pump and electric motor forming a unit and being carried by a bracket or other means in any suitable position, for example at the side of or below the chassis. Preferably the electric motor 25 circuit is switch controlled from the dash-board and obtains its power from the normal accumulator carried by the vehicle.

In a still further particular arrangement, handle, lever or like means are provided (for example 30 on the dash-board) for setting the valve controlling means into a position for erecting the hood or collapsing the hood; subsequent to such setting, the electric motor controlling the rotary pump being brought into circuit by suitable 35 switch means.

In order that the invention may be better understood it will now be described with reference to the accompanying drawings, in which:

Fig. 1 is a diagrammatic side elevation of a 40 portion of the chassis of a motor road vehicle with a folding hood constructed according to one method of carrying the invention into effect pivotally attached thereto, the diagram showing the general installation and with the hood in the 45 erected position.

Fig. 2 shows a similar view to Fig. 1 but of a fragment of the parts shown in Fig. 1 and these latter in the collapsed position of the hood.

Fig. 3 shows a diagram of a portion of the 50 installation shown in Fig. 1 but somewhat more detailed.

Fig. 4 shows a similar view to Fig. 3 but of a modified method of carrying the invention into effect.

Fig. 5 shows a sectional view of a preferred form of double-acting cylinder and ram assembly for the purposes of the invention.

Fig. 6 shows in elevation and Fig. 7 in end view the preferred form of direct coupled electro-hydraulic unit for the purposes of the invention.

It should be understood that it is known to provide folding hoods comprising main pillars pivoted to the two sides of the vehicle, which have in turn pivoted thereto the rear sections of cant-rails, the said cant-rails having hinged to the front thereof front cant-rail sections, these front cant-rail sections being connected together from side to side by a cross bar which when the hood is erected is adapted to be engaged by suitable co-operative fastening means carried by the upper portion of the windscreen frame. Further, it is known to control the movements of the rear cant-rail section by extending this rearwardly and pivoting it to an anchoring link and to control the movements of the front cant-rail section through a front control link, this latter also controlling the movements of supplementary links for supporting a front stick or stretcher.

As shown in Fig. 1, it should be understood the structure illustrates the mechanism on one side of the vehicle, but (insofar as the hood and its framework are concerned) this structure is repeated on the other side of the vehicle. In Fig. 1, 10 is the main pillar pivoted at 11 and 12 the rear cant-rail section pivoted at 13 to the upper portion of the main pillar and having a rearward extension 14 pivoted to an anchoring link 15 having its main pivot at 16. To the rear cant-rail section is hinged at 17 a front cant-rail section 18, 19 being the front control link pivoted at 20 to an upper extension of the main pillar 10, the control link 19 having pivoted thereto a link 21 in turn pivoted to another link 22 attached to the front cant-rail section, the links 21, 22 supporting between them a transversely extending stick or stretcher 23. This latter, together with a front cross bar 24, with a stick or stretcher 25 carried between the upper extensions of the pillars 10 and with similar sticks or stretchers 26 and 27 carried by extendable members 28 and 29 suitably pivoted, support between them in the usual manner the hood material 30, this latter being suitably attached to the body of the vehicle at the rear, for example at 31.

Thus far, the general structure is known but it has been usual for the pivots 11 on the two sides to be pivoted to the bodywork or coachwork of the vehicle and according to a feature of the present invention these pivots 11 have their bearing in stiffened structures 32 forming an integral part of or attached to the chassis members 33. Thus it will be realized the whole framework of the hood can be built with and erected on the chassis without connection of any nature to the bodywork.

The front cant-rail links are connected to two links 34 and 35. The first of these has its lower end pivoted at 36 to the front cant rail section and its upper end to the link 19 at 37, whilst the second of these is pivoted at 38 to the rear cant-rail section and its upper end to the pivot 37. Preferably, and as illustrated in the drawings, the two links 34 and 35 are of equal length and the distance of their pivots 36 from the hinge 17 is equal. However, this particular arrangement may be varied and the links may be of different lengths and their pivotal distance from the hinge 17 also may be varied. Further, in place of the pivot 37, which pivots the two links together,

being utilized as the pivotal connection for the front control links 19, such control links may be pivoted to either of the links in a position between the pivots 35 or 38 (as the case may be) and the pivot 37. Or again, in further constructions either of the links 34 or 35 may be extended beyond the pivot 37 and the front control link 19 pivotally connected to such extension.

The advantage given by the above-described construction is that the pull (or push) exerted by the link 19 on each side of the vehicle takes place with a substantially great leverage or moment with respect to the hinge 17 and further that the final closing action is braked. Additionally, when in the collapsed position (as shown in Fig. 2) the two links 34 and 35 do not hinder the folding action. Moreover, owing to the greater leverage or moment and to the general construction, it is possible, without exerting undue force, for both the movements of erecting and collapsing to be effected by pushes or pulls, derived from the movements of the main pillars, but applied through the front control links 19.

According to the invention the erection or the collapsing of the hood, or both, takes place by hydraulic means. This hydraulic means preferably comprises what may be termed an extensible strut formed by a cylinder and piston assembly. Such an assembly may be disposed on one side of the vehicle only or on both sides of the vehicle, but preferably the latter, and the preferred mounting is as follows.

One end of said assembly is pivoted to the chassis and the other end to the main control pillar. Thus when such an assembly is extended the pivotal movement of the main pillar takes place to effect the erection of the hood whilst when it is contracted the pivoted main pillar is brought to the collapsed position and through its movements brings the hood to the collapsed position.

The hydraulic assembly as illustrated in Figs. 1, 2, 3 and 5 is made double-acting. In Fig. 1 it is shown in the extended position and comprises a cylinder 42 pivoted to the chassis at 43 and having its ram or rod 44 pivotally connected at 45 to the main pivoted pillar 10. When in the extended position, as shown in Fig. 1, the erection of the hood is accomplished whilst in the contracted position as shown in Fig. 2 the hood is collapsed or lowered, the preliminary operation for this latter purpose being unfastening the fastening devices between the front cross bar 24 and the upper portion of the frame of the windscreen 46.

When in this condition, assuming the parts to be as shown in Fig. 1, then upon the ram or piston rod 44 being drawn into the cylinder 42, it causes the main pillars 10 to turn upon their pivots 11. This imparts movement to the rear cant rail 12 which is guided by the anchor link 15 and further imparts movement to the front control links 19 which through the link connections 35 and 34 imparts movement to the front cant rail section 18, this latter also being subject to the movement imparted to it through the hinged connection 17 from the rear cant rail portion 12. As a result the parts are brought at the end of the collapsing action to the position shown in Fig. 2.

The reverse operation will be readily understood and is caused by the projection of the piston rods 44 from their cylinders 42, which imparts movements to the main pillars 10, these in turn imparting movements to the other parts.

Towards the end of the erecting movement, owing to the position of the parts, a braking effect on the final lowering action (to the erected position) of the front cant rail sections takes place owing to the arrangement of the structure of the links 34 and 35.

The cylinder and piston assembly as used in Figs. 1 and 2 is shown in section in Fig. 5. This comprises a cylinder 47 having an end 48 with an inlet 49 and trunnions constituting the pivot 43. The other end is comprised by a cap 50 with a bore or bearing for the piston rod 51 guarded by a gland 52, the rod 51 terminating in an eye or the like 53 for the pivot 45 attached to the main pillar 10. The cap 50 has an inlet 54 for fluid.

The inner end of the piston rod is formed or provided with a piston 55 having a gland 56. This latter preferably is expandable so that in one direction it can act as a seal whilst in the other direction it need not seal.

As will be understood, the surface areas of the piston 55 are unequal. On the one side the area is that of the internal cross section of the cylinder 47 whilst on the other side (owing to the presence of the piston rod 51) it is of less area, and can be made of half the area of the other side.

Consequently in operation if the pressure fluid is admitted through the inlet 49 and through the aperture 54, it operates on the two sides of the piston, but owing to the greater area on the one side, although the pressure on the two sides is equal, the effective resultant force projects the piston rod 51 to cause the erection of the hood. Owing, however, to the equality of pressure on the two sides of the piston, the seal 56 is not necessary and by the said equalization of pressure the channel-shaped sealing member 56 is not expanded, but may even permit leakage or passage from one side of the piston to the other.

When, however, the hood is to be brought to the collapsed position, then the pressure fluid is admitted only through the aperture 54 on to the portion of the piston of less area and the liquid on the other side of the piston is free to flow out through the apertured inlet 49. Thus the pressures on the two sides of the piston are unequal but owing to the disposition of the channel section sealing member 56, the pressure on the side of the piston of less area effectively expands this sealing member to prevent leakage. Further it should be understood that if, as has been assumed, the effective area on one side of the piston is half that on the other side, in the particular circumstances of operation described, the effort for moving the hood to the erected position or for collapsing the hood is equal.

A method by which the pressure fluid (such as oil) is fed to the cylinder to attain the objects just described is illustrated in Fig. 3 and also (to some extent) in Fig. 1.

In these figures, 57 is a two-way rotary pump driven by an electric motor 58 in the circuit of an accumulator 59 which circuit also includes a switch 60. 61 is the outlet from the pump and 62 the inlet, this latter communicating with a supply reservoir 63, 64 being a pipe branched between the supply 63 and the inlet 62. This branch 64 has therein a valve 65 and on the other side passes, by a conduit 66, to the apertured inlet 49.

A conduit 67 is branched on the conduit 66 and includes a valve 68 therein aligned with the

valve 65 so that the two valves 65 and 68 are controllable from a common handle 69 in such manner that when the one valve is closed the other is open. On the other side of the valve 68 a conduit 70 is arranged which is branched on to a conduit 71 leading from the outlet 61 of the pump and communicating with the inlet 54 of the cylinder 47.

As indicated in Fig. 1, the switch 60 and the handle 69 are located on the dash or fascia board 10 of the vehicle whilst the supply reservoir 63 comes beneath the bonnet, the accumulator 59 being the usual accumulator utilized on a vehicle, the electric motor 58 and pump 57 being arranged as a unit and attached in a suitable position to a side frame 33 of the chassis.

The operation will be readily understood; assuming the parts to be in the position shown in Fig. 2, if it is desired to erect the hood the valve 68 is opened and the valve 65 closed. Upon closing the switch 60 the pump supplies pressure fluid from the outlet 61 through the conduit 70 to the inlet 54 in communication with the side of the piston having the smaller area, this pressure being indicated by the dotted arrow 72 (Fig. 5). The pressure fluid also from the outlet 61 passes through the conduit 70 through the opened valve 68 to the conduit 66. From this conduit 66 it cannot pass by the valve 65, which is closed, but passes to the apertured inlet 49 which admits the pressure fluid to the surface of the piston having the larger area, this pressure being indicated by the dotted arrow 73. This, as before explained, causes the movement of the piston and piston rod to effect the erection of the hood, the action taking place in preferred arrangements on each side of the vehicle.

To bring the hood to the collapsed condition, the valve 68 is closed and the valve 65 opened, the circuit of the electro-motor being again closed by the switch 60. This causes the pressure fluid, as before, to pass by the conduit 71 to the inlet 54 into the cylinder to press upon the portion of the piston of smaller diameter, this pressure being represented by the full-line arrow 74. The pressure fluid, however, cannot pass back through the conduit 70 and through the valve 68 as this latter is closed. However, the fluid in front of the portion of the piston of larger area is not under pressure and is free to flow out through the apertured inlet 49 into the conduit 66. It cannot pass the valve 68 which is closed, but it can pass the valve 65 which is open. It thus enters the conduit 64, from whence it is free to pass to the inlet 62 of the pump and to the reservoir 63. The full-line arrow 75 to the right of the piston in Fig. 5 represents such passage of the liquid.

Further, the dotted arrows in Fig. 3 represent the passage of the liquid for the erection of the hood and the full-line arrows the passage of the liquid for the collapse of the hood.

It is preferred to couple the motor 58 and pump 57 together as a unit and in a preferred construction the arrangement is such as shown in Figs. 6 and 7 in which a flanged bracket 76 has attached on the one hand the flange of the motor 58 and on the other hand the flange of an aligned pump 57, the latter being axially coupled with the motor shaft through a flexible coupling 77. In some cases in place of the rotary pump being directly connected to the shaft of the electric motor, it may be connected thereto through suitable reduction or other gearing.

In place of a power pumping system, a hand pumping system may be utilized, whether the pis- 75

ton and cylinder assembly, or assemblies, are single or double-acting.

Fig. 4 indicates a hand pumping assembly where 18 is a hand pump operable from a lever 19. 5 This may be detachable and fitted into position where required. For example, the pump may be located beneath a suitable apertured floorboard capable of having the handle or extension 19 fitted therethrough to be operated through a suitable stroke to actuate the pump. The pump 18 is in connection with a supply reservoir 80 and the installation includes a valve 81 capable of being set into various positions for permitting the pressure fluid to be supplied to the cylinder and piston assembly as may be required. In this arrangement again, the valve assembly if required may be set from the dash or fascia board.

If required, spring means may supplement the action of the hydraulic piston and cylinder assemblies. For example, a compression spring can be arranged on the exterior of the cylinder and co-operate with an abutment thereon and with an abutment on the piston rod, so that the compression of the spring assists the preliminary 25 erecting action and brakes the final collapsing action. Again, in some cases, the piston may include therein a spring adapted to project inwardly and cushion itself against the lower end of the cylinder towards the end of the collapsing 30 action. In this way it would cushion the said action and store stress to assist the preliminary erecting action.

The invention is not limited to the precise forms or details of construction described as 35 these may be varied to suit particular cases. For example, in the hydraulic systems any usual safety or relief valves may be incorporated in any part of the system they may be desired; or again, in connection with the power drive slipping or other clutches may be incorporated automatically to come into operation when the load 40 passes a predetermined limit. This effect may also be assured, if desired, by making the switch controlling the running of the electric motor of the push variety so that it only operates when 45 the hand presses thereon.

Again, as a further main modification, although the invention has been particularly described as relating to a cant-rail divided into 50 two portions, it should be understood that some or all of the features of the invention can be utilized with a cant-rail having a single section or having more than two sections. In this way the invention is rendered suitable for small single-door vehicles or larger vehicles of the limousine 55 variety.

What I claim and desire to secure by Letters Patent of the United States of America is:—

1. Folding hoods for vehicles which have main pillars, comprising extensible and retractable hydraulic piston and cylinder assemblies on each 5 side of the vehicle each pivoted at one end to a main pillar of the hood and at the other end to the chassis of the vehicle, each piston and cylinder assembly being double-acting and having at each end of the cylinder inlet means for pressure fluid, the said inlet means being in connection with a conduit system including a pump, a reservoir for fluid and controlling valve means, the two surfaces of the piston having different 10 areas and the valve controlling means of such 15 nature that either the smaller surface of the piston or both surfaces are available to the pressure fluid according to the valve setting, substantially as and for the purposes set forth.

2. Folding hoods for vehicles as claimed in 20 claim 1 in which the piston is provided with a one-way sealing gland adapted to seal the action in one direction and to permit the passage of pressure fluid from one surface of the piston to the other when pressure is applied to both 25 surfaces of the piston, for the purposes set forth.

3. Folding hoods for vehicles as claimed in 30 claim 1 in which the piston is provided with a one-way sealing gland adapted to seal the action in one direction and to permit the passage of pressure fluid from one surface of the piston to the other when pressure is applied to both 35 surfaces of the piston, and manual means for operating the pump, for the purposes set forth.

4. Folding hoods for vehicles as claimed in 40 claim 1 in which the piston is provided with a one-way sealing gland adapted to seal the action in one direction and to permit the passage of pressure fluid from one surface of the piston to the other when pressure is applied to both 45 surfaces of the piston, and power means for operating the pump, for the purposes set forth.

5. Folding hoods for vehicles as claimed in 50 claim 1 in which the piston is provided with a one-way sealing gland adapted to seal the action in one direction and to permit the passage of pressure fluid from one surface of the piston to the other when pressure is applied to both 55 surfaces of the piston, and in which the pump is a rotary pump having a shaft directly coupled through a cushioning coupling to the spindle of an electric motor, for the purposes set forth.

FRANCIS HENRY REDFERN. 65
